ILLUMINATED LOCK KEYHOLE MEANS

Russell S. Gohn, San Diego, Calif.

Application May 9, 1938, Serial No. 206,843

2 Claims. (Cl. 240—2.13)

My invention relates to a means for illuminating keyholes to lock and the objects of my invention are:

5 First, to provide an electric light in direct communication with the keyhole of a lock so that the light shines outwardly through the keyhole to its outer extremity;

10 Second, to provide a lock means of this class in which the support for the light is made an integral part of the lock structure and communicates directly with the keyhole through the key receiving washers and cylinder;

15 Third, to provide a means of this class which is applicable for use in connection with the lighting or starting lock for automobiles or for door locks or similar structures;

20 Fourth, to provide a means of this class which may be controlled by the light circuit or otherwise;

25 Fifth, to provide a means of this class which is applicable for use in connection with the tumbler or washer locks; and

Sixth, to provide a means of this class which is very simple and economical of construction, easy 25 to apply, efficient in its action and which will not readily deteriorate or get out of order.

With these and other objects in view as will appear hereinafter, my invention consists of certain novel features of construction, combination, 30 and arrangement of parts and portions as will be hereinafter described in detail and particularly set forth in the appended claims, reference being had to the accompanying drawing and to the characters of reference thereon which form 35 a part of this application in which:

Figure 1 is a side elevational view of an automobile ignition lock with my means applied in relation thereto shown mounted on a fragmentary portion of a dash of an automobile; Fig. 2 40 is a front elevational view of the same taken from the line 2—2 of Fig. 1 but omitting the dash of the automobile; Fig. 3 is a sectional view taken from the line 3—3 of Fig. 2 showing some of the parts in elevation to facilitate the illustration; Fig. 4 is a diagrammatic view showing the keyhole light and socket removed from its casing 45 and Fig. 5 is a sectional view of a fragmentary portion of my means taken from the line 5—5 of Fig. 3.

50 Similar characters of reference refer to similar parts and portions throughout the several views of the drawing:

The lock tumbler casing 1, light extension casing 2, key receiving tumblers 3, key receiving cylinder 4, insulation cylinder 5, switch member

6, insulation plate 7, lamp bulb socket 8, and lamp bulb 9 constitute the principal parts and portions of my illuminated lock keyhole means.

The lock disclosed and described herein is designed for use as an ignition lock for automobiles, but it is obvious that my lighting means may be used in connection with other classes of locks.

The casing 1 is cylindrical in form provided with a threaded exterior 1a at one end adapted 10 to be threaded into a socket D¹ on the dash D of the automobile. It is provided with a bore 1b in which is mounted the key receiving cylinder 4 at its front end as shown best in Fig. 3 of the drawing. It is provided with a key receiving slot 4a which communicates through slot 4b shown best in Fig. 5 of the drawing with a slot 1c in the casing 1 shown best in Figs. 3 and 5 of the drawing. Mounted in this key receiving cylinder 4 is a plurality of tumbler members 3. 15

In this case there are shown five, each supported in an upward position by means of springs 4c, all of which are conventional and are adapted to be operated by the key for locking and unlocking the lock, and it will be noted that the slots 4b 20 and 1c are cut directly through the cylinder 4 and the tumbler members, thus providing direct communication through the slot 1c, 4b and the keyhole 4a. This casing 1 is provided with a 25 smaller bore 1d in which is mounted an insulated plug member 5. This plug member 5 is provided with a central recess 5a in which is mounted a pin 6a which extends inwardly from the switch member 6 and around which is mounted a spring 6b tending to hold the member 6 30 outwardly into engagement with the insulation plate 7 which insulation plate is mounted in the 35 backwardly extended end of the casing 1 and it is provided with contact members 7a which connect with wires 7b which connect with any lighting system to be controlled by the lock. The cylinder 4, tumblers 3 and springs 4c, insulation cylinder 5, switch member 6, insulation plate 7 40 are of conventional type and no part of my present invention. Integrally connected with the one side of the casing 1 is the light extension casing 2 which is preferably positioned on a slight angle from a right angle to said casing and it is 45 hollow cylindrical in form and mounted in this member 2 is a lamp bulb socket 8 and lamp bulb 9 which are of conventional type, it being noted that the bulb 9 is positioned in close proximity to the slot 1c which communicates directly with the key receiving slot 4a in the cylinder 4 and 50

55

the cylinder 4 and tumblers 3 are cut away to provide direct light communication from the lamp bulb 9 to the keyhole 4a.

The wires 8a from the socket 8 may communicate with the electric light circuit from which the wires 7b and 7b are connected or may be separately connected as desired. It will be here noted that when the bulb 9 is lighted, the light is directed through the slot 4c, 4b and outwardly 10 through the key receiving slot 4a so that it is illuminated so that anyone can readily find the keyhole for operating locks.

It will be further noted that this lock may be used for various purposes as desired.

15 Though I have shown and described a particular construction, combination and arrangement of parts and portions, I do not wish to be limited to this particular construction, combination and arrangement, but desire to include in the scope 20 of my invention the construction, combination and arrangement substantially as set forth in the appended claims.

Having thus described my invention, what I claim as new and desire to secure by Letters Patent is:

1. In an illuminated lock keyhole means of the class described, the combination of a lock tumbler casing provided with light conducting slotted tumblers therein, a light transmitting opening in the side wall of said lock tumbler casing communicating with the slots in said tumblers, said lock tumbler casing provided with a lock keyhole arranged to conduct light passing through said tumblers and a light bulb in communicative relation with said light transmitting opening in said lock tumbler casing. 5

2. In an illuminated lock keyhole means of the class described, the combination of a lock tumbler casing provided with light conducting slotted tumblers therein, a light transmitting opening 15 in the side wall of said lock tumbler casing communicating with the slots in said tumblers, said lock tumbler casing provided with a lock keyhole arranged to conduct light passing through said tumblers, a light bulb in communicative relation with said light transmitting opening in said lock tumbler casing, a casing for said light bulb positioned on one side of said lock tumbler casing. 20

RUSSELL S. GOHN. 25
